UNITED STATES PATENT OFFICE.

ERNST F. PRIDDAT, OF CHICAGO, ILLINOIS.

FASTENER.

SPECIFICATION forming part of Letters Patent No. 762,599, dated June 14, 1904.

Application filed August 12, 1903. Serial No. 169,288. (No model.)

To all whom it may concern:

Be it known that I, ERNST F. PRIDDAT, a citizen of the United States, residing at Chicago, in the county of Cook and State of Illinois, have invented a new and useful Improvement 5 in Fasteners, of which the following is a specification.

My invention relates to an improvement in the class of flexible sheet-metal fasteners employed for clamping intersecting wires, cord, and the like at the points of intersection, as in wire fences, cord-tied packages, and the like.

On cord-tied packages where the cord (including twine and string) is crossed upon itself at different points when any pains are taken to form a fastening at a point of intersection this is commonly done by looping the free end of the cord about the section thereof 15 it is caused to cross and sometimes by knotting it at each intersection. It is the experience of those who thus pack goods for shipment that the cord used for tying a package breaks at the intersections, with the effect of 20 undoing the package before delivery, unless the cord be knotted at the intersections, and the knotting operation is not commonly resorted to because of the trouble it incurs and the time it consumes. In the case of wire 25 fence it is objectionable to twist the wires together at the intersections because of the work involved and of the tendency that results from the twisting of weakening the wires.

The object of my invention is to provide as 35 a means for conveniently, cheaply, securely, and expeditiously fastening the cord or wires at the intersections a novel construction of flexible sheet-metal clamp which shall be cheap to manufacture, convenient of application, and peculiarly effective in its purpose.

The manner of using my improvement is the same whether it be applied to a cord-tied package or to fence-wires; but for the purposes of illustration it is shown in the first- 45 named connection in the accompanying drawings, to which reference is had.

Figure 1 is a perspective view of a cord-tied package having my improved fastener applied to the cord intersection for securing it; Fig. 50 2, a similar view showing by way of diagram

the fastener in the initial position of its application to a looped cord intersection, and Fig. 3 a perspective view of the fastener enlarged over the scale observed in Fig. 1.

At A is represented a form of package fastened with a cord B tied with a cord intersection at x, shown to be looped.

My improved sheet-metal fastener C, as illustrated, comprises a body portion a of any desired form, having a jaw b on one edge open on one side of the body and two relatively separated jaws b', formed on an adjacent edge at right angles to the jaw b and open on the opposite side of the body, and its surfaces, which embrace the cord-sections at the intersection x, 60 are represented as roughened by providing them with numerous points the better to clench them upon the cord. The fastener is more particularly designed for application to a looped section of the cord; but it is also applicable to an intersection which is not looped. 65

To apply the fastener, the jaws b' are first introduced under the cord to straddle the loop into the initial position represented in Fig. 2, when the device is turned over on the engaged 70 cord-section as a fulcrum into the position represented in Fig. 1, whereby the loop is somewhat strained with the advantage of tautening it, and the jaw b is thereupon engaged with the cord-section adjacent to it, when the 75 jaws are clenched to fasten them.

While the foregoing description is restricted to flexible sheet metal as the material out of which to form my improved fastener and though that particular material is preferred, 80 it may without departure from my invention be formed out of any other suitable material.

What I claim as new, and desire to secure by Letters Patent, is—

As a new article of manufacture, a flexible 90 sheet-metal fastener for the intersections of cord, wire, and the like, comprising a body portion having a jaw open at one side of the body portion and two jaws, spaced apart, at a right angle to said jaw, open at the opposite side of said body portion.

ERNST F. PRIDDAT.

In presence of—

WALTER N. WINBERG,
W. B. DAVIES.
